Application September 14, 1938, Serial No. 229,808
In Sweden September 15, 1937

15 Claims. (Cl. 253—16.5)

The present invention relates to elastic fluid turbines and has particular reference to turbines of the double rotation type. Still more particularly the invention relates to double rotation turbines of the kind in which the motive fluid is expanded in one or more axial flow blade systems after having been previously expanded in one or more radial flow blade systems in the same turbine. For convenience such turbines will herein-
10 after be referred to as radial-axial flow turbines.

If the great merits claimed for modern turbines are to be achieved, the turbine construction must be such as to permit the admission of motive fluid to the turbines at high pressures and at high
15 temperatures and also the turbine speeds must be high. As a result, the turbines must be subjected to high stresses due to temperature conditions, usually referred to as temperature stresses, and also high mechanical stresses due to the centrifugal forces resulting from the high speeds of
20 operation. In addition to the mechanical stresses caused by centrifugal forces, there are also heavy stresses occasioned by the transmission of torque between the different parts of the turbine, particularly when the turbine is overloaded as for example when an electric generator driven by the turbine is short circuited.

One of the principal objects of the present invention is to improve the construction, particularly the rotor construction, of turbines of the kind under consideration so that those parts which are subjected to high stresses due to temperature are relieved, as far as possible, from high values of mechanical stresses, and vice versa.

35 By segregating to a great extent the two classes of stresses into different turbine rotor parts, numerous advantages in turbine construction are obtainable which permit, among other things, of constructing the blade systems so as to obtain
40 highly efficient operation of turbines with large capacity, without subjecting the parts to total stresses of dangerously high values.

To this end the rotor construction is of built-up form comprising a plurality of disc-like rotor
45 portions wherein the moving blades of the axial flow blade system of the rotor are secured to two or more axial flow turbine discs which are carried by an intermediate disc portion rigidly connected to the turbine shaft and provided with passages
50 extending substantially in axial direction for the admission of motive fluid to the radial flow blade system. The intermediate disc portion can readily be designed to withstand the stresses imposed upon it in accordance with such design and the radial flow disc portions of the rotor are thereby

released from the stresses due to the torques to which they would be subjected if constructed in accordance with prior forms of apparatus in which the axial flow turbine discs are carried by and transmit their torque through the radial flow
5 turbine discs.

It is a matter of fact that the intermediate disc portion is not subjected to extreme stresses due to centrifugal forces, which stresses on the other hand are of higher value in the radial flow discs. 10 It is therefore also highly advantageous to dispose the passages for the supply of motive fluid to the radial flow blade system in the intermediate disc portion rather than in the radial flow disc. Such an arrangement is also superior to 15 previously proposed arrangements in which the passages for the supply of motive fluid are arranged in the turbine shaft which is subjected to peripheral stresses from the entire blade system of the rotor.
20

In accordance with the novel construction of the present invention, the extent of the axial flow blade system can be enlarged as compared with systems heretofore employed, in a convenient manner and without risk, with the result 25 that greater outlet areas and a greater value of the sum of the squares of the peripheral velocities can be obtained. Because of this it is further possible to shorten the blades of the outermost blade ring of the radial flow system and thus avoid the necessity for using special construction for such blade ring.
30

Preferably, the axial flow turbine discs are connected to the intermediate disc portion in such manner that each axial flow disc is carried by the 35 intermediate disc portion by means of a separate connection or bond, the nature of which is such that the bond need not transmit more than the torque from one axial flow disc and thus may be made with comparatively small dimensions. This 40 arrangement offers the further advantage that the force acting on the intermediate disc portion may be distributed in a favorable manner and in certain instances a construction embodying the principles of the invention also renders possible 45 the bleeding of motive fluid without the necessity of weakening the radial flow discs by bleeder passages.

A further object of the invention is to increase the number of blade rings in the radial flow blade 50 system without the necessity of increasing the outer diameter of the radial flow system, thus rendering it possible to admit motive fluid directly at very high pressures without using a special high pressure turbine to partially expand the 55

motive fluid before it is admitted to the radial axial flow turbine.

To this end the invention contemplates that at least the inner radial flow blade rings shall be carried by radial flow turbine disc portions each of which is connected, either directly or indirectly, to the corresponding turbine shaft and that the disc portions of the rotor connecting the same with the turbine shafts are provided with inlet passages for supply of motive fluid which extend substantially parallel to the turbine shafts and with the radial flow discs projecting inwardly toward the axis of rotation of the turbine to a radius less than the distance between the axis of the inlet passages and the axis of rotation. In a preferred embodiment of the invention, at least the inner radial flow blade rings are carried by radial flow disc portions which are substantially T-shaped in cross-section, disposed in such manner that the flange portion of the T extends in generally radial direction and carries the blade rings, while the web portion extends generally axially and is located radially outside of the inlet passages to the radial flow blade system, which passages are substantially parallel to the turbine shafts.

Other and more detailed objects of the invention and the advantages to be derived from its use in different specific forms of turbine construction will become apparent from the ensuing portion of this specification in which there is described by way of example several embodiments of turbine structure for carrying the invention into effect.

35 In the accompanying drawings illustrative of such embodiments and forming a part hereof: Fig. 1 is a more or less diagrammatic central axial section of part of a turbine embodying the invention;

40 Fig. 1a is a view on enlarged scale of a detail of construction suitable for embodiment in a turbine of the kind shown in Fig. 1; and

45 Figs. 2 to 8, inclusive, are all views like Fig. 1 but showing different specific arrangements of rotor construction embodying the principles of the invention in different detailed manner.

Referring now to Fig. 1, 10 indicates the shaft member proper of one of the two oppositely rotating shafts of a double rotation turbine, to which shaft member there is rigidly secured the hub portion 12. Rigidly fixed to the hub 12 there is secured a disc portion 14 constituting an intermediate disc and having axially extending passages 16 and 18 therethrough. At one of its sides 55 the disc 14 is provided with radially spaced flanges 20 and 22 and at its opposite side two similar flanges 24 and 26. The construction further provides two axial flow turbine discs 28 and 30, the former being provided at one side with a flange 32 projecting between the flanges 20 and 22 and the latter disc being provided with a flange 34 projecting between the flanges 24 and 26. These flanges are provided with radial bores in 65 which are located pins 36 and 38 which transmit the torque developed by the axial flow discs to the intermediate disc and further serve to keep the several discs in their properly aligned axial positions while permitting a certain degree of 70 radial movement of expansion between the discs.

A radial flow disc 40 is connected to disc 14 by means of bolts 42 and this latter disc is also advantageously connected to permit of relative radial movement with respect to disc 14. Construction permitting such axial movement may

advantageously be as shown in Fig. 1a in which the bolts 42 rigidly retain a flanged ring 44, the flange of which projects between cooperating flanges on the disc 1. The cooperating flanges are bored to receive radially extending pins 46 which serve to hold the parts in proper axial position and which also permit the desired relative expansive movement in radial direction. In the construction described, the axial flow discs 28 and 30 and the radial flow disc 40 may be said 10 to be carried by the intermediate disc 14 and as the term "carried" is employed in this specification, it will be understood that between the parts said to be carried one by another, it is meant that there is a connection between the 15 two which transmits torque but does not transmit from one to the other of the parts stresses due to centrifugal forces which are separately absorbed by the connected parts.

In the construction described, the inner radial flow blade system is formed by a series of radial flow blade rings 48 carried by the disc 40, which rings interleave with a series of blade rings 50 carried by the rotor disc 52 which forms a part of the oppositely rotating rotor of the turbine. 25 The latter is usually, but not necessarily, of generally similar construction, and for an understanding of the principles of the present invention it is sufficient to describe in detail the construction of but one of the turbine rotors. 30

In the present embodiment an outer radial flow blade system is also provided, the blade rings 54 of which are carried by the axial flow disc 28. The latter disc has fixed thereto rows of moving axial flow blades 56 and 58 while the second axial flow disc 30 has fixed thereto a third row of axial flow blades 60. Cooperating with these blades are rows of fixed axial flow guide blades 62, 64, and 66, fixed to the stationary turbine structure indicated generally at 68. 40

The disc member 14 has secured thereto a labyrinth member 70 between which and a stationary labyrinth member 72 there is provided a radially extending labyrinth packing indicated generally at 74. Axially extending labyrinth packing 76 is 45 also provided around the hub 12 of the turbine shaft.

Motive fluid is supplied through the inlet conduit 78 which terminates in a chamber 80 from which chamber the fluid flows through the inlet 50 passages 16 in disc 14 to a collecting chamber 82.

As will be observed from the drawings, the radial flow disc portion 40, which is subjected to extremely high temperatures and also to high stresses due to centrifugal force, is not required 55 to take up or transmit the torque developed by the axial flow turbine discs, the torque from these discs being transmitted to the intermediate disc portion 14, through which portion the torque is transmitted directly to the turbine shaft. Also, 60 it will be noted that the radial flow disc portion 40 is not weakened by passages, such as passages 16, for the supply of motive fluid to the radial flow blade system. These passages are instead provided in the intermediate disc portion 14 65 which is not subjected to as high stresses because of centrifugal force as is the radial flow disc portion.

It will further be observed that the above described construction also makes it possible to project the radial flow disc portion 40 toward the axis of the turbine to a comparatively short radius r which is materially less than the distance a between the axis of the inlet passage 16 and the axis of the turbine. As a result, a larger 75

number of radial flow blade rings is obtainable in the radial flow system without increasing the outer diameter thereof, as compared with previous forms of construction. As a consequence 5 higher initial motive fluid pressures may be employed than would otherwise be possible.

Since the torque from the axial flow discs is transmitted by the intermediate disc portion 14 which has no blades, the number of axial flow 10 discs and moving axial flow blade rows can be increased and as a consequence a larger value of the sum of the squares of the peripheral velocities is obtainable. This in turn makes possible 15 the use of relatively shorter blades in the last row of the radial flow system which is obviously advantageous. Since the different axial flow discs are carried by separate connections or bonds, the latter may be made relatively small in size.

20 In the embodiment illustrated, the rotor disc 52 is indicated as being provided with a passage 84 for the admission of additional motive fluid upon overload and a further passage 86 is provided for bleeding motive fluid at an intermediate pressure. These expedients are known. By 25 use of the present construction a further bleeder passage 88 is obtained between the radial flow disc 40 and the axial flow disc 28, which passage it will be observed is obtained without the necessity of weakening the radial flow disc by providing special transverse bleeder passages extending therethrough.

It will further be observed that in accordance 35 with the present construction the cross-section of the radial flow turbine disc portion is preferably of T-form, the flange portion 40a of which is generally radial in extent and carries the radial flow blade rings 48 while the web 40b extends in generally axial direction and radially 40 outside the inlet passages for the motive fluid.

In the remaining embodiments, the general 45 turbine construction is basically similar to that just described and for the sake of brevity and clarity, only the differences in construction as compared with the embodiment illustrated in Fig. 1 and pertaining to the application of the principles of the present invention will be pointed out.

In the embodiment shown in Fig. 2, the axial 50 flow blade system comprises three axial flow discs 90, 92, and 94, providing four rows of moving axial flow blades 96, 98, 100, and 102. In the present instance the end discs 90 and 94 are secured directly to the intermediate disc portion 55 14 by means of bonds 104 and 106 respectively of the radial pin type, while the intermediate disc 92 is secured by means of the bond 108 to the disc 94. In other respects, the construction is essentially the same as that shown in Fig. 1.

60 In the embodiment shown in Fig. 3, two axial flow discs are employed which are attached to the intermediate disc portion 14 in a manner similar to that shown in Fig. 1, but in addition there is provided a further bond 110 of the radial pin type between the axial flow disc 28 and the outer periphery of the flange part 40a of the radial flow disc portion 40.

In the embodiment illustrated in Fig. 4, as well 70 as in the ensuing embodiments, the intermediate disc portion and the radial flow disc portion are made integral, with the web part 40b of the T-shaped radial flow disc portion extending axially to merge with the intermediate disc portion and be secured directly to the turbine shaft. It will 75 be observed, however, that in this form of con-

struction as in the previously described embodiments, the inlet passages 16 extend through the intermediate disc portion in such manner that the radial flow disc portion carrying the radial flow blades is not weakened by these passages. In 5 the present arrangement the two axial flow discs 112 and 114, the former having a single row of blades 116 and the latter having two rows of blades 118 and 120, are carried at the periphery of the flange part 40b of the radial flow disc portion, disc 112 being carried by a bond 122 of radial pin form and disc 114 being carried by a bond 124 consisting of radial pins passing through interleaving flanges. A thickened portion of the flange part 40b provides for a bleeder passage 15 126.

The construction shown in Fig. 5 is generally similar to that illustrated in Fig. 4, but differs therefrom by the fact that the first axial flow disc 112, at the inlet of the axial blade system, 20 is carried by the second axial flow disc 114 through the intermediate of a ring bond 128.

In the embodiment illustrated in Fig. 6, the radially outer part of the radial flow disc 40 is of generally U form in cross section, one leg or 25 flange of the U being formed by the outer flange part 40a of the radial flow disc portion and the other leg or flange 130 of which projects radially outwardly from the intermediate disc portion with which the web of the T-shaped section of the 30 radial disc portion merges. The web part 132 of the U is formed integrally with the intermediate disc portion and also constitutes a part of the web 40b of the generally T-shaped cross section of the radial flow disc portion. As will be observed, the web of this U-shaped portion of the section, as well as the web of the T-shaped portion of the section, both lie outside the inlet passages 16.

The flange part 130 carries the two axial flow 40 blade discs 28 and 30 by means of a common radial pin type bond connection indicated at 134.

In the embodiment illustrated in Fig. 7, the radial flow disc portion 40, which is integral with the intermediate disc portion 14, is T-shaped in cross-section and in this embodiment the axial flow disc 28 is carried by a radial pin type bond 136 connecting the disc with the outer periphery of the flange part 40a of the radial flow disc portion, while the axial flow disc 30 is carried by a pin type bond 138 secured to the web part of the T section.

In the embodiment illustrated in Fig. 8, the axial flow blade system comprises three discs 140, 142, and 144, disc 140 being carried by disc 142 through the medium of a bond 146 and disc 142 in turn being carried by disc 144 through the medium of a bond 148. The radial flow and intermediate disc portions are in this embodiment formed integrally and provide the characteristic 55 T-shaped cross-section as well as U-shaped cross-section previously described in connection with Fig. 6, the flange 130 of the U-shaped portion of the cross-section being connected by means of a bond 150 to the axial flow disc 144 which in turn carries the remaining axial flow discs.

In addition the intermediate axial flow disc 142 carries an outer or auxiliary radial flow disc 152 by means of a bond 154. The inner or main radial flow disc portion carries the blade rings of the inner portion of the radial flow blade system while the auxiliary disc carries intermediate radial flow blade rings 156. The outer radial flow blade rings 54 are in this instance also carried by 70 the intermediate axial flow disc 142.

As will be evident from the foregoing, the general principles of the invention may be incorporated in a wide variety of specific turbine rotor designs and certain features of construction within the scope of the invention may be used to the exclusion of others. It is accordingly to be understood that the scope of the invention is not limited to the forms of construction hereinbefore described by way of example, but is to be considered as embracing all forms of structure falling within the scope of the appended claims when they are construed as broadly as is consistent with the state of the prior art.

What is claimed is:

15. 1. In a double rotation radial-axial flow type turbine, a turbine shaft and a built-up rotor including one or more axial flow disc portions and a radial flow disc portion, said radial flow disc portion being substantially T-shaped in cross-section and providing a generally radially extending flange part carrying radial flow blade rings and a web part extending in generally axial direction, radially outside of passages extending in substantially axial direction through the rotor structure for admission of motive fluid to the inlet of the turbine blade system.
20. 2. A turbine rotor including the structure set forth in claim 1 in which said flange part extends radially outwardly to a radius greater than the inner radius of at least one of said axial flow discs.
25. 3. A turbine rotor including the structure set forth in claim 1, characterized by the provision of an intermediate disc portion secured to the shaft and carrying said web part and at least one of said axial flow discs.

30. 4. A turbine rotor including the structure set forth in claim 1, characterized by the provision of an intermediate disc portion secured to the shaft at a place axially offset from said flange portion and with which said web part integrally merges, the portion secured to the shaft having passages extending therethrough for admission of motive fluid to the inlet of the turbine blade system.
35. 5. In a double rotation radial-axial flow type turbine, a turbine shaft and a built-up rotor including one or more axial flow disc portions and a radial flow disc portion, said radial flow disc portion having a cross-section including a generally U-shaped part having legs extending outwardly in generally radial direction, one of said legs carrying radial flow blade rings, the other of said legs carrying at least one of said axial flow disc portions, and the web of said U-shaped part lying radially outside inlet passages passing through the rotor for admission of motive fluid to the inlet of the blade system of the turbine.

40. 6. A rotor for a double rotation radial-axial flow type turbine including three axial flow disc portions of which the first portion, considered in the direction of flow of motive fluid, is carried by the second portion and the second portion is carried by the third portion.
45. 7. A turbine rotor including the structure set forth in claim 6, characterized by the provision of a plurality of serially arranged radial flow blade systems of which the inner system is carried by a disc portion transmitting torque to the turbine shaft independently of said axial flow disc portions and the remaining radial flow blade systems transmit their torque to the second of said axial flow disc portions.
50. 8. In a double rotation radial-axial flow type turbine, a turbine shaft and a built-up rotor including one or more axial flow disc portions and a

radial flow disc portion, said radial flow disc portion being substantially T-shaped in cross-section and providing a generally radially extending flange part carrying radial flow blade rings and a web part extending in generally axial direction, radially outside of passages extending in substantially axial direction through the rotor structure for admission of motive fluid to the inlet of the turbine blade system, said flange part extending radially inwardly to a radius less than 10 the distance from the axes of said passages to the axis of rotation of the turbine.

9. In a double rotation radial-axial flow type turbine, a turbine shaft and a built-up rotor including one or more axial flow disc portions and a radial flow disc portion, said radial flow disc portion being substantially T-shaped in cross-section and providing a generally radially extending flange part carrying radial flow blade rings and a web part extending in generally axial direction, radially outside of passages extending in substantially axial direction through the rotor structure for admission of motive fluid to the inlet of the turbine blade system, said flange part also carrying one or more of said axial flow discs.

10. In a double rotation radial-axial flow type turbine, a turbine shaft and a built-up rotor including one or more axial flow disc portions and a radial flow disc portion having a cross-section including a generally U-shaped part having legs extending outwardly in generally radial direction, one of said legs carrying radial flow blade rings, the other of said legs carrying at least one of said axial flow disc portions, the web of said U-shaped part lying radially outside inlet passages passing through the rotor for admission of motive fluid to the inlet of the blade system of the turbine, and there being an intermediate disc portion integral with said U-shaped part extending inwardly of said passages and secured to the turbine shaft.

11. In a double rotation radial-axial flow type turbine, a turbine shaft and a built-up rotor including a plurality of axial flow disc portions and an intermediate disc portion carrying said axial flow disc portions and rigidly fixed to said shaft, said intermediate disc portion having passages extending therethrough in substantially axial direction for admission of motive fluid to the inlet of the blade system of the turbine, and said intermediate disc portion carrying axial flow disc portions on both of its sides.

12. In a double rotation radial-axial flow type turbine, a turbine shaft and a built-up rotor including a plurality of axial flow disc portions and an intermediate disc portion carrying said axial flow disc portions and rigidly fixed to said shaft, said intermediate disc portion having passages extending therethrough in substantially axial direction for admission of motive fluid to the inlet of the blade system of the turbine, the axial flow disc portion having the last row of moving blades in the path of flow of the motive fluid being carried directly by said intermediate disc portion and the remaining axial flow disc portions being carried by the last mentioned axial flow disc portion.

13. In a double rotation radial-axial flow type turbine, a turbine shaft and a built-up rotor including a plurality of axial flow disc portions and an intermediate disc portion carrying said axial flow disc portions and rigidly fixed to said shaft, said intermediate disc portion having pas-

5 sages extending therethrough in substantially axial direction for admission of motive fluid to the inlet of the blade system of the turbine, a passage for bleeding motive fluid from an intermediate stage of the turbine being provided between the axially outer surface of a radial flow disc portion and the inner part of one or more of said axial flow disc portions.

10 14. In a double rotation radial-axial flow type turbine, a turbine shaft and a built up rotor including a plurality of axial flow disc portions and an intermediate disc portion carrying said axial flow disc portions and rigidly fixed to said shaft, said intermediate disc portion having passages 15 extending therethrough in substantially axial direction for admission of motive fluid to the inlet of the blade system of the turbine, a passage for bleeding motive fluid from an intermediate stage of the turbine being provided between the axially outer surface of a radial flow disc portion and the inner part of one or more of said axial flow

disc portions, said passage extending through said intermediate disc portion.

15. In a double rotation radial-axial flow type turbine, a turbine shaft and a built up rotor including one or more axial flow disc portions and a radial flow disc portion, said radial flow disc portion having a cross-section including a generally U-shaped part having legs extending outwardly in generally radial direction, one of said legs carrying radial flow blade rings, the other 10 of said legs carrying at least one of said axial flow disc portions, the web of said U-shaped part lying radially outside inlet passages passing through the rotor for admission of motive fluid to the inlet of the blade system of the turbine, 15 and one or more passages for bleeding fluid from an intermediate stage of the turbine being provided which passages extend through the axially outer leg of said U-shaped part.

ALF LYSHOLM.
GUSTAV KARL WILLIAM BOESTAD.

20
